Edward H. Foote.

UNITED STATES PATENT OFFICE.

EDWARD H. FOOTE, OF SOMERVILLE, MASSACHUSETTS.

AUTOMATIC BOOK-MARK.

SPECIFICATION forming part of Letters Patent No. 284,404, dated September 4, 1883.

Application filed February 19, 1883. (Model.)

To all whom it may concern:

Be it known that I, EDWARD H. FOOTE, a citizen of the United States, residing at Somerville, in the county of Middlesex and State 5 of Massachusetts, have invented a new and useful Automatic Book-Mark, of which the following is a full, clear, and exact description and specification.

The object of my invention is to provide a 10 cheap, simple, and convenient device which can be attached to any book having stiff covers, which will afford a ready means of at once opening the book at the place at which it was last open before without having to turn the 15 leaves back and forth, and which will be self-adjusting, allowing the leaves to be turned without being touched itself, so that the book may be read or used from the first page to the last without touching the mark, which 20 automatically shows at any time the book is taken up the place at which it was last closed. I attain this object by the use of the device shown in the accompanying drawings, in which—

25 Figure 1 is a side elevation or view; Fig. 2, a view from above, and Fig. 3 a view from beneath, of the device in the position shown in Fig. 1. Figs. 4 and 5 show the device attached to a book; and Figs. 6, 7, and 8 show 30 different equivalent forms of the part of the device by which it is attached to the book.

Similar letters refer to similar parts throughout the several views.

The device consists of a piece of spring-wire, 35 A B, of suitable length and gage, bent into a coil, A C D E, of nearly two full turns, Fig. 1, then carried straight to F, where it is bent at right angles nearly in the plane of the coil, forming the arm F B. It is also bent, as 40 shown at G, Fig. 2, at the upper part of the coil, where it crosses the edge of the book-cover.

To attach the device to a book, the coil is sprung apart at A C D, slipped over the back-cover, and pressed down until the bend at G, 45 Fig. 2, rests upon the edge of the cover and the straight portion E F is parallel with the edge of the book, the arm F B entering between the leaves at the desired place and

about one or two inches from the bottom of 50 the book, and exerting, by virtue of the spring inherent in the wire and allowed by the method of its attachment to the cover, an elastic pressure upon the leaves between it and the back-cover. The method of attachment will 55 be plainly seen in Figs. 4 and 5, the leaves being represented as cut away in Fig. 4 to show the inside of the cover, and Fig. 5 representing the book closed, showing the outside of the cover. 60

In use, the arm F B having been placed in its proper position between the leaves, all that it is necessary to do to turn one or more leaves is to take hold of the leaf or leaves at the upper corner, P, Fig. 4, and raise up, at the same 65 time pulling slightly in the direction indicated by the arrow R S, Fig. 4, so as to draw the leaf out from under the arm F B. In order that this may be done easily, it is necessary that the arm F B be placed near the bottom 70 of the book.

That portion of the device which clasps it to the book may be made in a different form from the coil A C D E, Figs. 1, 2, and 3. This coil is undoubtedly at once the cheapest, simplest, and best for the large majority of cases; 75 but such arrangements of the wire as, for instance, shown in Figs. 6, 7, and 8 might prove more advantageous in a few cases.

The principle of the device and its principal 80 and essential part being the bent arm B F E, fastened to the book-cover in such manner that it always exerts an elastic pressure upon the leaves between the arm B F and the cover to which the device is fastened, any form of the 85 wire between E and A which will secure this end may be used.

In Fig. 8 the short arm goes inside the book-cover and the twisted portion of the device outside. 90

Having thus fully described my invention, what I claim as new, and for which I desire to obtain Letters Patent, is—

A device for an automatic book-mark, consisting of a spring-wire, A B, Fig. 1, of suitable length and gage, bent at right angles at F, Fig. 1, and also bent into a coil at E, as shown in Figs. 1, 2, and 3, which coil shall 95

serve to fasten the device securely to the book-cover, as shown in Figs. 4 and 5, and at the same time act to some extent as a spring, opposing, in conjunction with the inherent elasticity of the wire E F B, an elastic resistance to any motion of E F B across or in the plane of the cover, thus causing the arm F B to exert at all times an elastic pressure upon

the leaves between it and the cover to which it is attached, all substantially as shown and described.

EDWARD H. FOOTE.
